UNITED STATES PATENT OFFICE.

MAURICE LACHMAN, OF NEW YORK, N. Y., ASSIGNOR TO UNIVERSAL ELECTRIC WELDING COMPANY, OF LONG ISLAND CITY, NEW YORK, A CORPORATION OF NEW YORK.

PROCESS OF CONSTRUCTING WINDOW-SASHES.

1,152,741.

Specification of Letters Patent.

Patented Sept. 7, 1915.

Original application filed November 15, 1911, Serial No. 660,373. Divided and this application filed January 22, 1915, Serial No. 3,704.

To all whom it may concern:

Be it known that I, MAURICE LACHMAN, a citizen of the United States, and a resident of New York, in the county of New York and State of New York, have invented certain new and useful Improvements in Processes of Constructing Window-Sashes, of which the following is a specification.

My present invention relates to a process 10 of constructing metal window sashes and particularly to the method of locking the members thereof together at their intersections.

The object of the invention is to simplify 15 the mode of constructing a window sash whereby the sash can be more quickly made and will be cheaper, simpler and more efficient than when a mechanical joint is employed.

20 With this end in view the invention consists in the improved process of constructing metal sash having locked joints as herein-after more particularly described and then specified in the claims.

25 In the accompanying drawings, Figure 1 illustrates a front elevation of a metal window sash constructed in accordance with this invention, one panel only being shown. Fig. 2 is a rear elevation of the same showing two of the finished joints. Fig. 3 is a cross-section taken on the line 3—3 Fig. 1. Fig. 4 is a perspective view illustrating the manner of assembling the members at the joint.

35 The complete window structure may be composed of any number of sash bars or members 1, 2, arranged to intersect each other at any desired distance apart, each of the members preferably being of a general T-shape in cross-section. The sash members or bars are made of any desired metal, each member comprising a longitudinal web 3 surmounted by a laterally disposed molding 4 symmetrically arranged

40 with regard to the web 3. The upper surface of the molding is preferably provided with a longitudinal bead 5. The members or bars are preferably of solid metal rolled or otherwise suitably shaped.

45 At each desired point of intersection of the members the molding 4 is mitered at each side of the web 3 by removing a section of the molding as shown at 6. The molding is cut away, when the members are

to intersect each other at right angles, at 55 an angle of 45°, the miter extending to the web 3 and the inner edges of the miter being separated by a space 7 equal to the width of the web 3. The miters being disposed alike in each sash member, the operation of 60 providing them is a simple one and may be effected by punching out the parts or cutting them away in any desired manner.

The member 1 is provided with a slot 8 piercing the material of the web 3 in line 65 with the apex of the miter 6 at each joint. The slot 8 preferably starts at the lower edge of the web 3 in the member or bar 1 and extends into the web for any desired distance but leaving the bead 5 of the member 1 continuous. The member or bar 2 is provided with a co-acting slot 9 similarly located with regard to the miter and which starts at the bead 5, penetrating into the member 2 for such distance that when the 70 members 1 and 2 are fitted together the bases of the slots 8 and 9 will seat on each other, at which time the upper surface of the beads 5 in the members 1 and 2 are located in the same plane and intersect each other as shown 75 in Fig. 1. It will be understood that the slot 9 is just as wide as the bead 5 so that when the members are fitted together the bead 5 will entirely close the opening of the slot 9 and form a smooth upper surface on 80 the finished sash.

The members or bars 1 and 2 are fitted to each other as indicated in Fig. 4 by pressing them laterally toward each other, the miters 85 closely fitting each other, the bead 5 closing the slot 9 and the web 3 of the member 2 fitting in the slot 8 of the member 1.

To effectively lock the members together against lateral displacement with respect to each other I weld the two members together 95 at their intersections by means of an extra piece or button of metal and utilizing the electric welding process. The welding may take place at either the upper surface of the joint or at the rear edge of the intersecting webs or at both. Preferably and as herein shown, the welding is effected at the edges of the web portions 3 as this is at the back of the sash and less trimming or finishing is necessary than if located at the beads 5. 100 To quickly carry into effect the locking of the parts and thus cheapen the construction I preferably cut away a small portion of

2

the continuous web 3 as indicated at 10 in the web of the member 2 at the point where said web intersects the web of the member 1. Over this intersection and in contact 5 with the four edges presented by the slot 8 and cut 10 is placed a small metal button or disk 11. Electric current is passed from the disk 11 to the intersecting webs 3 by means of suitably applied current-carrying electrodes, the metal of the disk coalescing with the edges of the slot 8 and cut 10 due to the passage of the current and pressure applied to force the softened metal together and the button down into the cavity 15 formed in the webs by the cut away portions whereby the two webs are securely welded together and any relative movement of either is prevented. The general operation and the apparatus necessary to carry 20 out the electric welding of parts is now so generally well known that any more detailed description of this step of the process is thought unnecessary.

It will be understood that the process as 25 specifically described is but the preferred one and that variations of the same may be practised without departing from the spirit of the invention as expressed in the appended claims.

30 This application constitutes a division of my application for patent for metal window sash, filed Nov. 15, 1911, S. N. 660,373.

What I claim as my invention is:—

1. The process of joining the intersecting 35 members of a metal window sash consisting in providing members having a web portion and a lateral molding, mitering each molding at the place of intersection, slotting the web portion of each member from 40 opposite edges, placing the slotted parts in intermeshed relation to bring the moldings in a common plane, placing a separate button over and spanning the intersection and

passing a welding current from one to the other and at the same time applying pressure to force the parts together to lock the members to each other. 45

2. The process of joining the intersecting members of a metal window sash consisting in providing members having a web portion 50 and a lateral molding, mitering each molding at the place of intersection, slotting the web portion of each member from opposite edges, placing the slotted parts in intermeshed relation, providing four shoulders in the web at the intersections, placing a metal button in contact with said four shoulders and passing a welding current from one to the other and at the same time applying pressure to force the button down 55 into the cavity formed by said shoulders. 60

3. The process of joining the intersecting members of a metal window sash consisting in providing members having a web portion and a lateral molding, mitering each molding at the place of intersection, slotting the web portion of each member from opposite edges, placing the slotted parts in intermeshed relation, forming a notch in the continuous web where it 70 passes through the slot of the other web whereby a sharp four-shouldered cavity is formed, placing a metal button spanning said cavity and in contact with the four shoulders and passing a welding current 75 from the button to the webs and at the same time applying pressure to force the parts together. 80

Signed at New York in the county of New York and State of New York, this 21st day of January A. D. 1915.

MAURICE LACHMAN.
